UNITED STATES PATENT OFFICE

GEORGE K. LEWIS, OF CHICAGO, ILLINOIS, ASSIGNOR TO MET-L-WOOD CORPORATION,
OF CHICAGO, ILLINOIS, A CORPORATION OF ILLINOIS

PRESSBOARD

Application filed October 18, 1928. Serial No. 313,240.

This invention relates to press boards for use in book-binding.

In finishing books, a final operation consists in placing the books between boards designed for the purpose and inserting the same into a suitable press, the boards being provided with beads along their edges adapted to engage the books to emphasize the groove portions intended to form the hinge connections with the backs of the books.

Heretofore such boards have been of wood and on account of the heavy stresses to which they are subjected in use, necessarily have been of excessive thickness to resist the stresses imposed thereon, and consequently take up much more space than is convenient or desired.

An object of the present invention is to provide a pressboard of this character made up of laminations of steel and wood affording exceptionally great strength with very small thickness, as compared to the press boards now in use.

A further object of the invention is to provide a laminated board of the character referred to, in which steel veneers form the outer-most laminations of the board, and the edges of the board so constructed as to provide the required bead in a novel and effective manner.

Still another object of the invention is to provide a headed construction along the edges of the boards wherein the veneers at the opposite sides of the board are utilized in forming the beads, and are so connected as to provide a reinforced bead and edge construction for the board.

Other and further objects of the invention will more fully appear from the description and claims hereinafter appearing.

In the drawings forming a part of this invention, Figure 1 is a plan view of a press board embodying my invention. Figure 2 is a fragmentary sectional view through one edge of the board, said view corresponding substantially to the line 2-2 of Figure 1.

Figure 3 is a fragmentary prospective view of a corner portion of the board showing the angle brackets used in connection therewith. Figure 4 is a fragmentary sectional view

similar to Figure 2, and disclosing a somewhat different embodiment of the invention. Figure 5 is a sectional view similar to Figure 4 showing still another embodiment of the invention. Figure 6 is a sectional edge view showing another embodiment of the invention. And Figure 7 is a fragmentary vertical sectional view through a pair of boards, showing the manner of use in connection with a book to be operated upon.

As shown in the drawings, the press board embodied in my invention comprises a body portion made up of a plurality of layers of plywood, indicated at 10, and opposite layers 11 and 12 of sheet steel. Interposed between the layers 11 and 12 and the body portion 10 are fabric sheets 13, preferably of a fuzzy surface texture flannel, adhesive being interposed between the body portion, the fabric sheets, and the metallic sheets, for the purpose of permanently bonding the layers together in a series of laminations forming a composite panel, relatively thin, but of great strength.

Along the marginal edge of each surface of the board is provided a bead indicated by the numerals 14 and 15. These beads are formed by turning up a flange portion 16 along the marginal edge of each of the steel sheets 11 and 12, which portions co-operate with a connecting strip 17 to complete the bead, and finish and reinforce the edge construction of the panel. The connecting strip 17 is preferably in a single piece, and formed to fit along the four edges of the board, and is substantially of channel shape for this purpose. The web 18 of the channel shape lies along the edge of the board, while the flanges are crimped over the marginal flanges 16 of the sheets 11 and 12, as clearly shown in Figure 2, the flanges forming the bead proper, while the web of the channel shape connects the edges of the two steel sheets in such manner that the strip reinforces the construction throughout, the web 18 being disposed at right angles to the pressure applied to the board, and the bead being reinforced by the out-turned marginal flange portions on the metallic sheets. The strip 17 at each corner is preferably depressed for

the reception of the legs of an angle bracket 190 as best shown in Figure 3. The legs of the angle bracket lie within the depressed portions, and screws are extended through said legs, through the strip 17, and into the body portion. All of the four edges of the board are of the same construction shown in section in Figure 2.

Through the provision of a press board of this character, comprising laminations of steel and wood, great strength is assured, and a minimum thickness obtained; also the necessary bead formation is provided by a reinforced edge construction which serves to finish the edges of the board and reinforce the bead. By the use of press boards of the character described, a great amount of space is saved with no loss in strength, and the beaded construction is of a strong and durable character.

In Figure 4 there is shown a somewhat different embodiment of the invention, wherein the metallic veneers 19 and 20 are formed adjacent their marginal portions with integral off-set beads 200 and 210, the portions of the veneers outward of the beads, and indicated at 22 and 23, being relied upon to connect the veneers and finish the edge of the board. The marginal portion 22 is off-set as indicated at 24 so as to lap beneath the adjacent edge of the marginal portion 23, the overlapping portions being sealed and secured with solder. Although only one edge of the board has been described, it will be appreciated that all four edges of the press board, such as that shown in Figure 1, will be of like construction.

In Figure 5 the marginal portions 26 and 27, instead of having their edges overlapped are turned inwardly as indicated at 29 so as to be embedded in the body portion of the board, the marginal portions 29 being soldered together. Referring to Figure 6, a body portion 30 and veneers 31 and 32 are disclosed, the veneers along their marginal portions being beaded as indicated at 34 and 35, and insert strip 36 is accommodated within the beaded portions, and the flanges of the veneers beyond the beaded portions are secured to the strip by solder.

All of the constructions described have a marked advantage over the press boards as ordinarily provided in affording increased strength with a great decrease in thickness, and the reinforced beaded construction along the edges of the board serve not only to provide the necessary beading, but also to connect the metallic veneers of the board and present a smooth and finished appearance whereby the board may be readily manipulated and the presence of raw or unfinished edges avoided.

While I have herein shown and described what I consider the preferred manner of carrying out the invention, the same is merely

illustrative, I contemplate all changes and modifications which come within the scope of the claims appended hereto.

I claim:—

1. A press board made up of a plurality of laminations of fibrous material and metal, the metallic laminations being disposed to form the exterior surfaces of said board; and means including portions of said metallic laminations, providing a beaded construction along the marginal edge of said board.

2. A composite board of the character indicated, comprising a plurality of laminations of fibrous material and metal, the metallic laminations being disposed at the exterior surfaces of said board, the marginal edges of said metallic laminations being offset and connected to provide a reinforced edge construction, said edge construction having portions formed to provide a bead along the marginal surface of the board.

3. A board of the character described comprising a fibrous body portion and exterior veneers of sheet metal, the marginal edges of said sheet metal veneers being off-set to provide beads; and means connecting the ends of said metallic veneers along the edges of said board.

4. A board of the character described comprising a plurality of laminations of fibrous material and metal, the metallic laminations adjacent their marginal edges being provided with a beaded construction including off-sets in the metallic laminations, and connecting strips secured to the off-set portions of said metallic laminations.

5. A board of the character described comprising a plurality of laminations of fibrous material and metal, the metallic laminations adjacent their marginal edges being provided with a beaded construction including off-sets in the metallic laminations, and connecting strips secured to the off-set portions of said metallic laminations, said strip being disposed at right angles to the main plane of said board.

6. A press board of the character described comprising a fibrous body portion and exterior veneers of metal, the marginal edges of said veneers being connected together by a soldered joint, and portions of said veneers being off-set and formed into beads.

7. In a press board of the character described, a relatively thick body portion of fibrous material, and outer surface layers of relatively thin metal secured flatwise to the body portion, and a metallic edging connecting the metal surface layers and extending outwardly therefrom to furnish a marginal bead.

8. In a press board of the character described, a relatively thick body portion of fibrous material, and outer surface layers of relatively thin metal secured flatwise to the body portion, and an integrally formed me-

tallic edging connecting the metal surface layers and extending outwardly therefrom to furnish a marginal bead.

9. In a press board of the character described, a relatively thick body portion of fibrous material, and outer surface layers of relatively thin metal secured flatwise to the body portion, and an integrally formed metallic edging connecting the metal surface layers and offset outwardly from one of the metallic layers to form a marginal bead.

10. In a press board of the character described, including a corner portion, a relatively thick body portion of fibrous material, and outer surface layers of relatively thin metal secured flatwise to the body portion, and a metallic edging connecting the metal surface layers and offset outwardly from one of the metallic layers to form a marginal bead, the edging being recessed in the region adjacent to the corner, and a corner bracket lying in said recess and secured to said corner.

In witness that I claim the foregoing I have hereunto subscribed my name this 10th day of October, 1928.

G. K. LEWIS.
